US00D924872S

(12) **United States Design Patent** (10) **Patent No.:** **US D924,872 S**
(45) **Date of Patent:** **** Jul. 13, 2021**

(54) **KEYBOARD FOR ELECTRONIC DEVICE**

(71) Applicant: **SAMSUNG ELECTRONICS CO., LTD.**, Suwon-si (KR)

(72) Inventors: **Sung-Jin Yum**, Suwon-si (KR); **Min-Ah Koh**, Suwon-si (KR); **Hak-Do Kim**, Suwon-si (KR)

(73) Assignee: **SAMSUNG ELECTRONICS CO., LTD.**, Gyeonggi-Do (KR)

(**) Term: **15 Years**

(21) Appl. No.: **29/722,372**

(22) Filed: **Jan. 29, 2020**

(30) **Foreign Application Priority Data**

Aug. 16, 2019 (KR) 30-2019-0039213

(57) **CLAIM**

The ornamental design for a keyboard for electronic device, as shown and described.

DESCRIPTION

FIG. 1 is a front perspective view of a keyboard for electronic device, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the encircled portion 9 in FIG. 4; and,

FIG. 10 is an enlarged view of the encircled portion 10 in FIG. 8.

The even-dash broken lines illustrating portions of the keyboard for electronic device form no part of the claimed design. The dot-dash broken lines showing enlarged detail views are for annotative purposes only and form no part of the claimed design.

1 Claim, 10 Drawing Sheets
